UNITED STATES PATENT OFFICE.

MORTIMER NORDEN, OF NEW YORK, N. Y.

ELECTRIC-LAMP SOCKET.

SPECIFICATION forming part of Letters Patent No. 742,725, dated October 27, 1903.

Application filed February 24, 1903. Serial No. 144,608. (No model.)

To all whom it may concern:

Be it known that I, MORTIMER NORDEN, a citizen of the United States, residing in the borough of Manhattan, city, county, and State of New York, have invented an Improvement in Electric-Lamp Sockets, of which the following is a specification.

My invention relates to incandescent-electric-lamp sockets and supports, and particularly to sockets employed in surface wiring.

The object of my invention is to produce a socket in which not only electrical contact may be made with the line-wires to complete the circuit through the lamp and in which the said contact with the line-wires may not be disturbed, by the removal of other parts, but also in which the circuit through the lamp may be made when the said other parts are connected and broken when the said other parts are disconnected without the risk of contact with live conductors or the short-circuiting of the same.

According to my present invention the device is of elongated rectangular shape and comprises a cup member and a base member, both of which may be made of porcelain or other similar suitable material. The cup member is provided centrally with an integral cup-shaped portion extending appreciably on either side thereof, and the base member preferably corresponds in outline with the cup member. The cup member is provided exteriorly of its cup-shaped portion with openings placed in diametrically opposite positions and through which screws are passed, contacting not only with plates through which the circuit is made with the socket, but with other plates in the base member which are connected electrically with the line-wires. These screws complete the electric circuit extending to and through the lamp and also mechanically connect the cup member and the base member to hold the same together.

In the drawings, Figure 1 is a central transverse section of a lamp-socket, representing my invention. Fig. 2 is a plan of the cup member of the lamp-socket. Fig. 3 is a plan view of the base member, and Fig. 4 is an inverted plan of the cup member.

a represents the cup member, which is preferably of elongated rectangular form and

made of porcelain or other similar vitrified material and is provided with a central integral cup-shaped portion *a'*, which extends 55 to an appreciable distance beyond two opposite edges of the cup member. The cup-shaped portion *a'* is adapted to inclose the metallic lamp-socket *b*, which receives the base of the incandescent electric lamp. Ex- 60 teriorly of the cup-shaped portion *a'* and in diametrically opposite positions the cup member *a* is provided with openings 5 and 6. On the under side of the cup member *a* there are metallic plates *c* and *d*. The plate *c* is 65 secured to the cup member *a* by a screw 3, preferably passing through the central portion of the cup-shaped portion *a'*. The plate *d* is conveniently made with a semicircular portion 2, conforming generally with the 70 semicircular portion *b'* of the base of the metallic socket *b*. The plate *d* is secured to the cup member *a* and electrically connected to the metallic socket *b* by means of the screws 4.

e represents the base member, which is provided with the longitudinally-disposed central recesses 7, 8, and 9. The metallic contact-plate *f* is secured in the recess 7 by means of a screw 10, and a metallic contact-plate *g* is secured in the recess 8 by means of 80 the screw 11. These contact-plates *f* and *g* are provided with binding-posts 13, by which the line-wires may be held in electrical contact against said plates, the base being provided at its ends with recesses 12, through 85 which the line-wires *h* are carried to and led from the lamp-socket. The short edges of the base member *e* are provided with tongues 14, and the short edges of the cup member *a* are provided with recesses 15, into which the 90 tongues 14 are adapted to fit when the parts are placed in position. Screws *i* are employed and passed through the openings 5 and 6 in the cup member, through the metallic plates *c* and *d*, and into the contact-plates 95 *f* and *g* to complete the electric circuit and hold the parts of the socket together and in position, the recess 9 being of such depth that when the parts are in this relation the base of said recess will be in contact with the metallic plates *c* and *d*.

The base member *e* may be provided in suitable positions with holes 16, through which screws or other devices may be passed and

employed to secure the base member to a wall or other support.

I claim as my invention—

1. An electric-lamp socket, comprising a cup member and base member of porcelain or other suitable vitrified material, metal plates secured in recesses in the base member and with which the line-wires make contact, conductor-plates on the under side of the cup member and connections therefrom to the metallic lamp-socket and center thereof, and screws passing through apertures in said cup member outside of the socket, through the conductor-plates and into the plates of the base member to both complete the electric circuit and connect the parts.
2. An electric-lamp socket, comprising a cup member of elongated rectangular form made of porcelain or other suitable vitrified material, a base member of similar form and material having longitudinally-disposed central recesses, metal plates secured in said recesses and with which the line-wires make contact, metal plates on the under side of the cup member, screws passing through said cup member and securing said metal plates to the center of the cup-shaped member and to the metallic lamp-socket, and screws passing through apertures of the cup member at opposite points outside the cup-shaped portion, passing through said metal plates and engaging the plates of the base member to connect the parts and complete the electric circuit.
3. An electric-lamp socket, comprising a cup member of porcelain or other suitable vitrified material, and having a central cup-shaped portion and provided with openings exteriorly of the same and diametrically opposite each other, a metallic lamp-socket adapted to fit within said cup-shaped portion, metallic devices on the under side of said cup member, means for securing one of said metallic devices to said cup member, means for connecting the other of said metallic devices to the said cup member and electrically to said metallic lamp-socket, a base member of the same material and configuration as the cup member, other metallic devices secured in either end of said base, binding-posts by which line-wires may be secured to said other metallic devices, and means passing through said openings in the cup member for simultaneously holding the parts together and contacting electrically with both sets of said metallic devices to close the electric circuit through the lamp.
4. An electric-lamp socket, comprising a cup member of porcelain or other vitrified material and having a central cup-shaped por-

tion, and provided with openings placed at diametrically opposite points exteriorly of said cup-shaped portion, a metal plate on the under side of the cup member, means passing through the center of said cup-shaped portion and adapted to secure the said metal plate to the cup member, a metallic lamp-socket adapted to fit in the said cup-shaped portion, a second metallic plate on the under side of said cup member, means for securing the same to the cup member and electrically to the said metallic lamp-socket, a base member of the same material and configuration as the cup member, metallic plates secured in either end of said base member, binding-posts for securing line-wires to said plates, and screws passing through the said openings in the cup member, contacting with the plates secured on the under side thereof and screwing into the said plates secured in the base member to simultaneously hold the parts together and complete the electric circuit through the lamp.

5. An electric-lamp socket, comprising a cup member of elongated rectangular form and made of porcelain or other vitrified material and having an integral central cup-shaped portion and provided with openings placed at diametrically opposite points exteriorly of said cup-shaped portion, a metal plate on the under side of the cup member, a screw passing through the center of said cup-shaped portion and adapted to secure the said metal plate to the cup member, a metallic lamp-socket adapted to fit within the said cup-shaped portion, a metal plate having a semi-circular portion on the under side of said cup member, screws for securing the same to the cup member and connecting the same electrically to the said metallic lamp-socket, a base member of the same material and configuration as the cup member and having longitudinally-disposed central recesses, metallic plates secured to the recesses in either end of said base member, binding-posts for securing line-wires to the said plates, and screws passing through the said openings in the cup member, contacting with the plates secured on the under side thereof and screwing into the said plates secured in the base member to simultaneously hold the parts together and complete the electric circuit through the lamp.

Signed by me this 13th day of February, 1903.

MORTIMER NORDEN.
